(57) **CLAIM**

The ornamental design for a portable computer housing, as shown and described.

DESCRIPTION

FIG. 1 is a front view of the design for the portable computer housing in accordance with the present design;

FIG. 2 is a rear view of the design for the portable computer housing in accordance with the present design;

FIG. 3 is a top view of the design for the portable computer housing in accordance with the present design;

FIG. 4 is a left side view of the design for the portable computer housing in accordance with the present design; and,

FIG. 5 is a right side view of the design for the portable computer housing in accordance with the present design.

In these drawings, the solid lines illustrate the claimed ornamental design, whereas the broken lines illustrate environmental features that form no part of the claimed ornamental design.
